UNITED STATES PATENT OFFICE

OSCAR S. WINKLER, OF ESSEX, MARYLAND

DESIGN FOR A CHIMNEY CAP

Application filed April 4, 1929. Serial No. 30,757. Term of patent 7 years.

To all whom it may concern:

Be it known that I, OSCAR S. WINKLER, a citizen of the United States, residing at Essex, in Baltimore County and State of Maryland, have invented a new, original, and ornamental Design for Chimney Caps, of which the following is a specification, reference being had to the accompanying drawing, forming part thereof.

I claim:

The ornamental design for a chimney cap, as shown.

OSCAR S. WINKLER.
